UNITED STATES PATENT OFFICE

131,501

DESIGN FOR A GAME BOARD

Charles Armstrong Carty, Earlville, Iowa

Application December 3, 1941, Serial No. 104,451

Term of patent 7 years

To all whom it may concern:

Be it known that I, Charles Armstrong Carty, a citizen of the United States, residing at Earlville, in the county of Delaware and State of Iowa, have invented a new, original, and ornamental Design for a Game Board, of which the following is a specification, reference being had to the accompanying drawing, forming part thereof.

I claim:

The ornamental design for a game board, as shown.

CHARLES ARMSTRONG CARTY.
